(57) **CLAIM**

The ornamental design for a flexible optic, as shown and described.

DESCRIPTION

FIG. 1 is a perspective view of an embodiment of the ornamental design of a flexible optic.

FIG. 2 is a top view of the embodiment of the ornamental design of the flexible optic of FIG. 1.

FIG. 3 is a side/front/back view of the embodiment of the ornamental design of the flexible optic of FIG. 1.

FIG. 4 is a bottom view of the embodiment of the ornamental design of the flexible optic of FIG. 1.

FIG. 5 is a perspective view of another embodiment of the ornamental design of a flexible optic.

FIG. 6 is a top view of the embodiment of the ornamental design of the flexible optic of FIG. 5; and,

FIG. 7 is a bottom view of the embodiment of the ornamental design of the flexible optic of FIG. 5.

The broken-line disclosure in the views is understood to represent portions of the article in which the claimed design is embodied, but which form no part of the claimed design.

1 Claim, 7 Drawing Sheets
